Primary Examiner — Keli L Hill*Assistant Examiner* — Harold E Blackwell, II(57) **CLAIM**

The ornamental design for a mount for electronic devices, as shown and described.

DESCRIPTION

FIG. 1 is a front, first side, and top perspective view of a mount for electronic devices embodying the new design; FIG. 2 is a back, second side, and bottom perspective view thereof;

FIG. 3 is a top, first side, and front perspective view thereof; FIG. 4 is a front view thereof;

FIG. 5 is a back view thereof;

FIG. 6 is a second side view thereof, the first side view being a mirror image;

FIG. 7 is a top view thereof; and,

FIG. 8 is a bottom view thereof.

The broken lines in the drawings illustrate portions of a mount for electronic devices which form no part of the claimed design.
